PRINTER'S REGISTER HOOK

Filed March 31, 1930

Inventor
William F. Brügman

By John G. Atta.

UNITED STATES PATENT OFFICE

WILLIAM F. BRÜGMANN, OF CHICAGO, ILLINOIS

PRINTER'S REGISTER HOOK

Application filed March 31, 1930. Serial No. 440,232.

This invention relates to improvements in printer's register hooks for holding printing plates in position on the base and more particularly to that type of register hook having locking means at each end of the body of the hook.

Heretofore with hooks of this character it is necessary to operate the locking devices at each end of the hook separately, thereby resulting in two separate and distinct operations, with the result that when a great many hooks are employed, the number of operations of locking and unlocking the hook is greatly multiplied.

It is one of the objects of the present invention to provide in a hook of the character having locking means at both ends thereof, means whereby one of the locking elements will be operated by the operation of the other locking element.

A further object is to provide improved means for securing the plate holding jaw to the body of the hook.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which

Figure 1 is a longitudinal sectional view of a hook of this character constructed in accordance with the principles of this invention and showing the same applied within a groove in a base, a portion of the base being shown in section.

Figure 2 is a top plan view of Figure 1.

Figure 3 is a detail perspective view of the plate engaging jaw.

Figure 4 is a view taken on line 4—4, Figure 1.

Figure 5 is a bottom plan view of the hook.

Figure 6 is a detail perspective view of one of the locking members and one extremity of the connecting link.

Figure 7 is a perspective view of the other locking member with the other extremity of the connecting link.

Figure 8 is a detail perspective view of the securing members for connecting the plate engaging jaw to the body of the hook.

Referring more particularly to the drawing the numeral 10 designates generally the body portion of the hook which may be of any desired size and configuration, but is shaped to fit within the groove 11 of the base 12.

The numeral 13 designates generally the plate engaging jaw adapted to engage and rest against the edge of the plate 14.

Connected to and depending from the jaw 13 is an extension which is formed integral therewith, a portion of the extension spaced from the free end thereof being reduced as at 15 to form a shoulder 16, for a purpose to be set forth.

The numerals 17 and 18 designate generally securing members for securing the jaw 13 to the body portion of the hook and these members 17 and 18 are preferably of angle iron construction, the members having semi-circular recesses 19 opening through the proximate edges of the members. A portion 75 of the lower face of each of the members 17—18 beneath the openings 19 is enlarged as at 20.

The jaw 13 is connected with the body 10 of the hook by bringing the edges of the members 17 and 18 together so that they will engage over the shoulder 16 on the extension 15 and the shoulder 16 fits within the recessed portion 20 on the lower face of the members 17 and 18. The recesses 19 receive the reduced portion 15 of the extension on the jaw and the members 17 and 18 are secured together and to the body portion 10 of the hook in any desired or suitable manner, either by brazing, welding or in any other manner so that the jaw 13 will be connected to the body 10 for free rotary or pivotal movement with respect thereto on a vertical axis.

The top of the body 10 beneath the members 17—18 is recessed as at 21 for the reception of a gear 22 suitably mounted, and this gear 22 meshes with another gear 23 connected with a shaft 24 and the gear 23 has connected with it for rotation therewith a worm gear 25 which meshes with a rack 26 in 100

the groove 11 of the base 12 so that when the gear 22 is rotated the hook will be propelled in the groove 11.

The jaw 13 is provided with an opening 27 therethrough which registers with an opening in the gear 22 so that an implement may be inserted into the gear 22 and rotated in the usual manner.

10 A locking member 28 is provided at one end of the body and a locking member 29 is provided at the other end of the body.

15 The locking member 28 is provided with a shank 30 having an angular recess 31 opening through the top thereof. The shank 30 is inserted in a bearing in the body 10 and extends through the body, terminating adjacent the upper surface thereof. A nut or collar 32 is threaded upon the shank 30 from the top of the body and the collar is provided with a shoulder 33 to form a bearing in the members 17 and 18 so that when the nut or collar 32 is screwed upon the shank 30 the locking member 28 will be mounted for free rotative movement on a vertical axis, 25 which is accomplished by inserting an operating implement into the angular recess 31 in the shank 30.

20 The locking element 29 is secured to the other end of the body 10 by means of a bolt 34 having a head 35 and a portion 36 of a diameter less than the diameter of the head 35 and greater than the diameter of the shank of the bolt so as to form a shoulder 37 which abuts a portion of the body 10. The bolt 34 35 projects through the body 10 and also through the members 17 and 18 and a nut or collar 38 is threaded thereupon. This collar is provided with a shoulder 39 so that by 40 relatively adjusting the nut 38 and the stem of the bolt 34 the shoulder 37 and the shoulder 39 will prevent the parts from being drawn together to such an extent as would interfere with the free pivotal movement of the locking element 29, as will be understood.

45 The locking element 29 is operated by the operation of the locking element 28, and to that end there is provided a connecting link 40, one end of which is bent at an angle as at 41 and enters the locking element 29, the element 29 being provided with a cut away portion 42 so that the link will not interfere with the operation of the element.

50 The other end of the link 40 is provided with an angularly disposed portion 43 adapted to pivotally engage the locking element 28. This element 28 is provided with a horizontal groove or slot 44 opening through the lateral walls thereof, and a slot 45 opening through the bottom and one of the lateral faces of the locking element 28 and having communication with the groove 44, so as to permit of the attachment of the end of the link 40 with the locking element 28. This is accomplished by turning the element 28 and the link 40 in such a position with respect to

each other than the end 43 of the link will pass into the slot 45, after which it is raised to enter an opening in the locking element 28. The locking element is then rotated with respect to the link 40 so as to cause the link 40 to extend transverse to the slot 45 and enter the slot or groove 44.

70 It will therefore be manifest that with this construction and by inserting an operating implement in the shank 30 of the locking member 28 and rotating it, this rotary movement will be imparted to the locking element 29 and both ends of the body 10 of the hook will be simultaneously locked and unlocked, thereby reducing to a minimum 75 the number of operations necessary to lock and unlock the hook in the base, and at the same time provide a means whereby both ends of the body of the hook will be held seated in the groove 11.

80 85 If desired indicating marks 46 may be provided on the end of the shank 30 so as to indicate the position of the locking members 28-29.

90 Considerable difficulty has heretofore been experienced in connecting the plate engaging jaws 13 with the body of the hook, and with this improved construction and with the extension 15 formed integral with the jaw, the jaw may be connected to the body of the hook 95 for free swinging movement and firmly held in position by means of the fastening members 17 and 18.

100 While the preferred form of the invention has been herein shown and described, it is to be understood that various changes may be made in the details of construction and in the combination and arrangement of the several parts, within the scope of the claims, without departing from the spirit of 105 this invention.

110 What is claimed as new is:

1. A printer's register hook embodying a body portion adapted to be inserted into a groove in a base, separate locking means at the ends of the hook, and means responsive to the operation of one of the first said means for simultaneously actuating the other of said locking means.

115 2. A printer's register hook embodying a body portion adapted to be inserted into a groove in a base, separate rotative locking elements at the ends of said hook, and means forming a communication between said elements whereby the rotation of one of said 120 elements will simultaneously rotate the other element.

125 3. A printer's register hook embodying a body portion, separate rotative locking elements at the opposite ends of said body portion, and a link connecting said elements and pivotally connected to both, whereby the operation of one of the elements will be controlled by the operation of the other of the 130 said elements.

4. A printer's register hook embodying a body portion, separate locking elements at the opposite ends of said body each mounted for rotation about a vertical axis, and a link the ends of which are pivotally connected with the respective locking elements whereby the operation of one of said elements will rotate the other element. 70
5. A printer's register hook embodying a body portion, separate locking elements at the opposite ends of said body each mounted for rotation about a vertical axis, a link the ends of which are pivotally connected with the respective locking elements whereby the 10 operation of one of said elements will rotate the other element, and means for indicating the position of said locking elements. 80
6. A printer's register hook embodying a body portion, a locking element connected with the body for rotation about a vertical axis, said element having a horizontal groove therein opening through the upright walls of the element, there being a slot through one wall of said element and communicating with the groove, and an operating link having an upturned end connected with said element, the adjacent portion of the link operating in said groove and maintained against displacement when the link extends transversely of the groove. 85
7. A printer's register hook embodying a body portion adapted to be inserted into a groove in a base, separate locking elements adjacent the bottom of said body and located at opposite ends of the body to rotate on vertical axes, and a link connecting said elements and pivotally connected with each, whereby the operation of said elements will operate the other, said link operating in the groove in said base. 90
8. A printer's register hook embodying a body portion, a locking element disposed beneath a portion of said body, a fastening element passing through said locking element, a shoulder on said fastening element engaging the locking element, a second shoulder on said fastening element and engaging the said body, said fastening element passing through the base, and a collar threaded on the end of the fastening element for securing the parts together. 95
9. A printer's register hook embodying a body portion, locking elements adjacent the bottom of the body, a stem connected with one of said elements and passing through the body portion and shaped to receive an operating element through the top of said body, means for securing said stem to the body whereby said locking element will be rotatable about an upright axis, and means whereby the operation of one of said elements will cause the operation of the other of said elements. 105
10. A printer's register hook embodying a body portion, separate locking elements at 130
- the opposite ends of the body and rotatable about upright axes, means for rotating one of said elements, a link connecting the elements whereby the rotation of one of the elements will rotate the other, and propelling means for the hook disposed between said locking elements. 110
11. A printer's register hook embodying a body portion, a plate engaging element, a headed projection depending from said element, and anchoring members for said element, said members being provided with semi-circular recesses opening through edges of said members and adapted when the edges of the members are brought together to form an opening of a diameter less than the diameter of the head of said projection and into which opening the body of said projection is rotatably seated, said members being secured together and to said body portion. 115
12. A printer's register hook embodying a body portion, a plate engaging element, a projection depending therefrom, said projection being reduced in diameter intermediate its ends to form a shoulder, and securing members for connecting said element with said body portion for free rotation on an upright axis, said securing members being separated from each other connected with said body portion and engaging over said shoulder. 120
13. A printer's register hook embodying a body portion of integral construction, a plate engaging element, a projection depending from said element and having a reduced portion spaced from the free end thereof and circular in cross section, securing members for connecting the said element with said body, said securing members being fastened to said body portion to extend over said shoulder and abut each other, and a bearing in the abutting edges of said members in which the said reduced portion of said projection is freely rotatable. 125
14. A printer's register hook embodying a body portion of integral construction, a plate engaging element, a projection depending from said element and having a reduced portion spaced from the free end thereof and circular in cross section, securing members for connecting the said element with said body, said securing members being fastened to said body to extend over said shoulder and abut each other, and a bearing in the abutting edges of said members in which the said reduced portion of said projection is freely rotatable, said element and projection having an opening therethrough for the reception of an operating tool to propel the hook. 130
15. A printer's register hook embodying a body portion, separate locking elements adjacent each end thereof and spaced from each other in directions lengthwise of the body portion, and means whereby both of 135

said elements may be simultaneously operated by the operation of one of said elements.

16. A printer's register hook embodying a body portion, separate locking elements adjacent each end thereof and spaced from each other in directions lengthwise of the body portion, means whereby both of said elements may be simultaneously operated by the operation of one of said elements, in combination with a base having a groove to receive the hook, and a shoulder along the lateral wall of the groove and beneath which shoulder said locking elements are adapted to engage.

15 17. A printer's register hook embodying a body portion, separate locking elements adjacent each end thereof and spaced from each other in directions lengthwise of the body portion, means for simultaneously operating said locking elements, in combination with a base having a groove to receive the hook, and a shoulder along the lateral wall of the groove and beneath which shoulder said locking elements are adapted to engage.

25 18. A printer's register hook embodying a body portion, separate locking elements spaced from each other, means for simultaneously operating said elements, in combination with a base having a groove to receive the hook, and a shoulder along the lateral wall of the groove and beneath which shoulder said locking elements are adapted to engage.

35 19. A printer's register hook embodying a body portion, separate locking elements spaced from each other, means for simultaneously operating said locking elements, in combination with a base having a groove to receive the hook, a shoulder along the lateral wall of the groove and beneath which shoulder said locking elements are adapted to engage, and means for indicating the position of the said locking elements.

40 20. A printer's register hook embodying a body portion, separate locking elements spaced from each other and pivotally connected with the body, a link connecting the elements, and a stop into engagement with which a portion of the link between the elements moves in either active or inactive positions of the elements.

45 21. A printer's register hook embodying a body portion, separate locking elements spaced from each other and pivotally connected with the body, and means for limiting the locking movements of the elements.

50 In testimony whereof I have signed my name to this specification, on this 24th day of March, A. D. 1930.

60 WM. F. BRÜGMANN.
